[57] ABSTRACT

A portable fireplace screen arranged on a variable length pipe assembly which is mounted on a pair of angle irons which is variable in height. The angle irons are arranged at opposite ends of the pipe assembly and a ratchet and crank assembly is arranged at the top of one of the angle irons to enable the fireplace screen to be raised or lowered.

SHEET 2 OF 2

PORTABLE FIREPLACE SCREEN

BACKGROUND OF THE INVENTION

1. Field of Invention

The present invention relates to a portable fireplace screen and more particularly to a fireplace screen having means to vary the height of the assembly as well as a ratchet and crank assembly to vary the height of the screen.

2. Description of the Prior Art

Prior art fireplace screens have typically lacked means to control the height of the overall assembly as well as reliable means for controlling the height of the screen.

SUMMARY OF THE INVENTION

The general purpose of the present invention is to provide a portable fireplace screen which possesses none of the aforescribed disadvantages of the prior art. To attain this, the present invention provides a fireplace screen mounted on two pipes. The diameters of the pipes are such that one is arranged to have an end inserted in the other and slidable to expand the total length of the pipe assembly. A set screw arrangement on the pipes retains the length of the pipes stationary once the combination of the two pipes has been adjusted to the desired length. The pipes may thereby be arranged horizontally along the total length of the top of the fireplace.

The pipes are mounted on two angle iron assemblies that are each adjustable in height and secured by bolt means. A ratchet and crank assembly is arranged at the top of one of the angle iron assemblies. It is connected to the end of one of the pipes which is mounted on that angle iron to thereby enable the fireplace screen to be raised or lowered. The opposite end of the other pipe appears to be mounted on the second angle iron assembly which requires no ratchet or crank assembly.

Accordingly, an object of the present invention is to provide means to adjust the height of a portable fireplace screen.

Another object of the present invention is to provide means to adjust the overall height of a portable fireplace assembly.

A further object of the present invention is to provide crank and ratchet means for raising and lowering the height of a fireplace screen and locking the screen into position at a predetermined height.

Still another object of the present invention is to provide adjustable bolt means for securing angle irons on which a fireplace screen is mounted to adjust the overall height of a portable fireplace assembly.

Other objects, advantages and novel features of the present invention will become apparent from the following detailed description of the invention when considered in conjunction with the accompanying drawings.

BRIEF DESCRIPTION OF THE DRAWINGS

FIG. 1 is a front view of a fireplace with fireplace screen installed; and

FIG. 2 is a top view of an embodiment of the fireplace screen which is the subject of the present invention; and

FIG. 2A is a top view of the spindle and angle iron arrangement on which the right end of the embodiment shown in FIG. 2 is mounted; and

FIG. 2B is an end view of the spindle shown in FIG. 2A; and

FIG. 2C is a view of the pipe and gear arrangement at the left end of FIG. 2; and

FIG. 2D is a cross sectional view of the pipe shown in FIG. 2C; and

FIG. 2E is a side view of the gear arrangement shown in FIG. 2C; and

FIG. 2F is a top view of the spindle and angle iron arrangement on which the left end of the embodiment shown in FIG. 2 is mounted; and

FIG. 2G is a side view of the spindle shown in FIG. 2F; and

FIG. 2H is a front view of the spindle shown in FIG. 2F; and

FIG. 3 is a view of the ratchet arrangement of the present invention; and

FIG. 3A is a view of the crank handle which turns the ratchet wheel; and

FIG. 3B is an end view of the ratchet wheel; and

FIG. 3C is an end view of the gear mounted on the ratchet wheel shaft; and

FIG. 4 is a view of the left angle iron assembly of the embodiment shown in FIG. 2; and

FIG. 4A is a front view of the angle iron assembly shown in FIG. 4; and

FIG. 4B is a top view of the angle iron assembly shown in FIG. 4.

DESCRIPTION OF THE PREFERRED EMBODIMENT

Referring now to FIG. 1, there is shown a pipe assembly 10 and 11 with the pipe 10 having a diameter slightly less than that of pipe 11 and arranged to fit in pipe 11 as shown in greater detail in FIG. 2. The pipe assembly is supported by angle iron 12 on the right which is fastened to angle iron 13 by expansion connection 16. It is also supported by angle iron 14 on the left which is fastened to angle iron 15 by expansion connection 17. A crank handle 18 may be rotated manually to rotate a screen mounted on the pipe assembly 10 and 11 to raise or lower the screen.

The screen 20 is shown in FIG. 2 fastened to the pipes 10 and 11 by metal screws 21. The length of the pipe assembly may be adjusted by unfastening set screws 22. After the pipe assembly has been adjusted to the desired length, the set screws need only to be tightened to retain the pipe assembly at the desired length. Pipe 10 is mounted on a spindle 23 as shown in FIG. 2A. An end view of the spindle is shown in FIG. 2B. Pipe 11, a cross-sectional view of which is shown in FIG. 2D, is fastened to a gear 24 as shown in FIG. 2C. An end view of gear 24 is shown in FIG. 2E. The pipe 11 with gear 24 is mounted on spindle 26 as shown in FIGS. 2 and 2F. An end view of spindle 26 is shown in FIG. 2G and a front view is shown in FIG. 2H. The spindle 26 has a hole 28 through which shaft 29 is inserted.

Gear 30 is mounted on shaft 29 as shown in FIGS. 2 and 3. Gear 30 meshes with gear 24 as shown in FIG. 2. FIG. 3C shows an end view of gear 30. A ratchet 32 is mounted on shaft 29 as shown in FIG. 3. FIG. 3B is an end view of ratchet 32. The ratchet may be latched by ratchet latch 40 shown in FIGS. 4 and 4A. The crank handle 18 is mounted on the shaft 29 to manually rotate the shaft 29 and gear 30. The rotation of gear 30 in turn rotates gear 24 which rotates pipe 11. Pipe 10

60 and 61 are shown in FIG. 2. FIG. 3C shows an end view of gear 30. A ratchet 32 is mounted on shaft 29 as shown in FIG. 3. FIG. 3B is an end view of ratchet 32. The ratchet may be latched by ratchet latch 40 shown in FIGS. 4 and 4A. The crank handle 18 is mounted on the shaft 29 to manually rotate the shaft 29 and gear 30. The rotation of gear 30 in turn rotates gear 24 which rotates pipe 11. Pipe 10

rotates simultaneously by virtue of the fastening of pipe 10 to pipe 11 by set screws 22. Since screen 20 is fastened to pipes 10 and 11 by screws 21, as shown in FIG. 2, it is seen that the screen may be raised or lowered simply by rotating crank handle 18. The height of the screen may be fixed by simply engaging ratchet latch 40 with ratchet 32 to thereby maintain shaft 29, gear 30, gear 24, pipe 11, and pipe 10 in fixed positions.

FIG. 4 shows angle irons 14 and 15 which are coupled by guides 42. A nut 43 and screw 44 enable the height of the combination of angle irons 14 and 15 to be adjusted. As shown in FIG. 4A, the nut 43 is welded to angle iron 14. As shown in FIG. 4, screw 44 is threaded through nut 43 but not triangular sheet 46 which is welded to the top of angle iron 15. A top view of the nut 43, screw 44, and triangular sheet 46 arrangement is shown in FIG. 4B. The height of the fireplace assembly may be adjusted by simply turning screw 44 to adjust the relative positions of angle irons 14 and 15. It will be apparent that the height of the right angle iron assembly comprising angle irons 12 and 13 may be adjusted in a similar manner.

Thus, it is seen that the height of the portable fireplace may be adjusted by adjusting the angle irons 12 and 13 on the right and 14 and 15 on the left as shown in FIG. 1. The adjustment may be obtained by a nut a screw arrangement such as nut 43 and screw 44 which is threaded through a hole in triangular plate 46 as shown in FIG. 4.

The height of the fireplace screen may be manually adjusted by turning crank 18, shown in FIG. 3A, and latching ratchet 32, shown in FIGS. 3 and 3B, with ratchet 40, shown in FIGS. 4 and 4A. The width of the assembly may be adjusted by moving pipe 10 longitudinally within pipe 11. The position of pipe 10, with respect to pipe 11, may be fixed by set screws 22 shown in FIG. 2.

It is seen that by using different length angle irons 15 and different length pipes 10, the fireplace screen of the present invention may be adapted to any size fireplace opening that is square or rectangular.

After installation in the fireplace opening, there will be a decorative flashing placed in front of angle irons 14,15 and pipe 10,11, which serves to make the outward appearance more attractive and spark-proof.

Obviously many modifications and variations of the present invention are possible in the light of the above teachings. It is therefore to be understood that within the scope of the appended claims, the invention may be practiced otherwise than as specifically described.

What is claimed is:

1. A portable fireplace screen comprising:
horizontal rotatable supporting means for supporting

a fireplace screen;
vertical supporting means for supporting said horizontal rotatable supporting means at either end and adjustable in height;
means for manually rotating said horizontal rotatable supporting means to thereby raise or lower said fireplace screen;
said vertical supporting means comprising two sets of angle irons each arranged at one end of said horizontal rotatable supporting means with each set containing a nut having its edge secured to one of the angle irons in a set and being threadedly engageable to a screw means in contact with at least one other of said angle irons in each set to fix the position of at least one of the angle irons in each of said sets in relation to that of another angle iron in the associated set.

2. The device as described in claim 1 wherein each of said sets of angle irons contains guide means to guide the movement of at least one of the angle irons in each of said sets in relation to that of another angle iron in the associated set.

3. The device as described in claim 2 wherein said horizontal rotatable supporting means comprises a pipe assembly containing at least two pipes arranged concentrically with one of said two pipes having a diameter slightly less than that of the other of said two pipes and slideable within the other.

4. The device as described in claim 4 further containing set screw means for fixing the position of one of said two pipes in relation to that of the other of said two pipes.

5. The device as described in claim 1 wherein said means for manually rotating said horizontal rotatable supporting means contains a ratchet and latch assembly.

6. The device as described in claim 6 wherein said means for manually rotating said horizontal rotatable supporting means further contains a crank.

7. The device as described in claim 6 wherein said crank is coupled to said horizontal rotatable supporting means by a gear assembly.

8. The device as described in claim 7 wherein said horizontal rotatable supporting means comprises a pipe assembly containing at least two pipes arranged concentrically with one of said two pipes having a diameter slightly less than that of the other of said two pipes slideable within the other.

9. The device as described in claim 8 further containing set screw means for fixing the position of one of said pipes in relation to that of the other of said two pipes.
